DISPLAY MODULE FOR PAPERBACK BOOKS

Harold L. Hudson, Gregory G. Mt. Pleasant, and Robert K. Scherzer, Liverpool, N.Y., assignors to Gaylord Bros., Inc., Syracuse, N.Y.

Filed Feb. 20, 1973, Ser. No. 333,549

Term of patent 14 years

Int. Cl. D6—04

U.S. Cl. D6—139

FIG. 1 is a perspective view of a display module for paperback books showing our new design;

FIG. 2 is a side-elevational view on an enlarged scale of one segment with the tower rotated to be aligned with the frame;

FIG. 3 is a sectional view taken on line 3—3 of FIG. 2;

FIG. 4 is a top plan view; and

FIG. 5 is a top plan of a display module for paperback books showing a modified form of our new design on a reduced scale.

We claim:

The ornamental design for a display module for paperback books, substantially as shown and described.
